Patented Nov. 26, 1963

196,968

WINDOW WELL COVER

Sidney Merritt Polhemus, Jr., Forest Drive, R.F.D. 5,
Huntington, N.Y.

Filed Feb. 7, 1963, Ser. No. 73,473

Term of patent 14 years

(Cl. D13—1)

FIG. 1.

FIG. 2.

FIG. 5.

FIG. 1 is a perspective view illustrating the front-side of a window well cover showing my new design;

FIG. 2 is a perspective view illustrating the back of the window well cover;

FIG. 3 is a top plan view thereof;

FIG. 4 is a front elevational view thereof; and

FIG. 5 is a sectional view taken on line 5—5 of FIG. 3.

I claim:

The ornamental design for a window well cover, as shown.
